UNITED STATES PATENT OFFICE.

JOHN J. GROSS, OF TOLEDO, OHIO.

TRAIN-CONTROLLING APPARATUS.

1,256,129.

Specification of Letters Patent. Patented Feb. 12, 1918.

Application filed July 12, 1916. Serial No. 108,916.

To all whom it may concern:

Be it known that I, JOHN J. GROSS, a citizen of the United States, residing at Toledo, in the county of Lucas, State of Ohio, have 5 invented certain new and useful Improvements in Train-Controlling Apparatus; and I do hereby declare the following to be a full, clear, and exact description of the invention, such as will enable others skilled 10 in the art to which it appertains to make and use the same.

This invention relates to the class of train control device, and has particular reference to that type of control systems in which the 15 brakes are applied and the motive power is cut off through the medium of an obstruction operated control device.

As a primary object, my invention pur- 20 poses to provide a control device which utilizes pressure from the air system of a locomotive to set into operation the brake system and to cut off the motive power.

It is likewise an object of the invention to provide an obstruction operated control de- 25 vice which utilizes the pressure from the air system of either a steam locomotive or an electric locomotive to set into operation the brake system of the train or car and to simultaneously cut off the steam or to break 30 the control circuit.

Also, the invention contemplates the pro- 35 vision of a train control system which may be set for operation simultaneously with the setting of a signal against a train by the towerman, so that the operation of the system is wholly out of the hands of the engineer or motorman.

As a secondary object, my invention in- 40 cludes the construction of an improved type of distributing valve for distributing the pressure to the various parts of the system, and a particular form of obstruction or tripping device which co-operates with said valve to throw the control system into operation.

45 With the above and other objects in view, my invention will now be fully set forth and described, reference being had to the accompanying drawings.

In said drawings:—

50 Figure 1 is a side elevation of a portion of an electric car, in which my improved apparatus is installed, parts of the car being broken away to disclose the latter,

55 Fig. 2 is a sectional view, showing the parts of the invention with the proper con-

nections between the parts, and to the braking system,

Fig. 3 is a side elevation of the track ob- struction,

Fig. 4 is a section on line 4—4 of Fig. 3, 60

Fig. 5 is a section on line 5—5 of Fig. 2,

Fig. 6 is a section on line 6—6 of Fig. 2,

Fig. 7 is a diagrammatic side elevation of a locomotive having my invention applied thereto, 65

Fig. 8 is a section on line 8—8 of Fig. 7,

Fig. 9 is a transverse section through the obstruction controlled device of this form,

Fig. 10 is a section through an air check device, and 70

Fig. 11 is a part elevation and part sec- tional view of an old type of locomotive steam pipe supply with my cut-off valve.

In describing my invention, reference will first be had to the form which is used upon 75 electric cars or locomotives.

In Fig. 1 of the drawings 1 denotes the lower beams of a locomotive frame, which is mounted upon the trucks 2. The top of the car carries the usual trolley pole 3 and lead- 80 ing therefrom to the cab or front platform 4 is the feed wire 5. Located below the car, and being suspended from the beams 1 is a control device 6, which is adapted to be actuated by an obstruction 7 located along 85 the track-way 8, the functions of the control device being to apply the brakes to the car or train and to actuate a circuit breaker 9 which is preferably located in the cab at a suitable point within the front platform in- 90 closure, where it may be located in the cir- cuit of the main feed wire 5.

The control device consists essentially of a cylinder 10, adapted to withstand the air pressure from the air system, and is sub- 95 divided into a plurality of chambers from which the motive power is distributed for effecting the circuit breaker 9 and causing the setting of the brakes. Said cylinder 10 is arranged in vertical position, and has its 100 upper end closed by a head or plate 11. Outturned flanges 12 formed on the cylinder 10 at an intermediate point is a flange or ring 14, upon which is bolted the arms 15 of a yoke 16 whose lower end terminates in a bearing 17. Said bearing 17 supports, for vertical reciprocation a squared shaft 18 110

whose lower end is provided with rollers 19. The rollers 19 are carried by a shaft 20 which passes through a bearing 21 and are adapted to ride over the obstruction 7 when the latter is properly positioned. Threaded into the upper end of the shaft 18 is a stem or valve rod 22, which passes through the lower end of the cylinder 10 through a bushing 23. A transverse partition 24 formed 10 across the cylinder 10 carries a valve seat 25, upon which rests the valve 26, said valve 26 being carried by the stem 22. A port 27 formed through the partition 24 and through the valve seat 25 provides for the passage of 15 air pressure from the lower compartment or chamber 28 to the upper compartment or chamber 29. A piston chamber 30 is provided in the upper end of the cylinder 10 by a partition 31, and an extension 32 of 20 the stem 22 passes through the partition 31, a bushing 33 surrounding the stem to prevent the loss of pressure in the piston chamber 30. The upper end of the extension 32 is provided with a piston 34. Each of the 25 chambers 28, 29 and 30 is provided with a port formed in the wall of the cylinder 10, and the plate or head 11 of the cylinder is also provided with a port. The functions of these ports will appear hereinafter.

30 The compartment or chamber 29 is in normal communication with air pressure from the tank 35, which may be the major air supply for the car or train or which may be a sufficient receptacle. A pipe 36 leading 35 from the chamber 29 to a four-way valve 37 located in the cab or otherwise adjacent to the motorman's position and through said four-way valve connects by pipe 38 to the air tank. A pipe 39 is connected to the 40 chamber 28, and permits the passage of the air from the chamber 29 to the air line 40 by way of the port 27 when the valve 26 is elevated. An air check valve 41, which is 45 hereinafter more particularly described is located in the air line 40 in order to prevent back pressure.

A branch pipe 42, located between the air check 41 and the control device rises to the top of the cab 4 to the circuit breaker 9.

50 The circuit breaker 9 consists of a cylinder 43 having a head 44 and a bottom diaphragm 45, said diaphragm 45 being spaced inwardly from the end of the cylinder 43, and having a central boss or extension 46 which provides a bearing for a shaft 47. Within the 55 closed portion of the cylinder 43 the shaft 47 carries a piston 48, which is adapted to reciprocate in the cylinder, and thereby actuates a switch bar 49 which is carried on an 60 upper extension 50 of the shaft 47. Said switch bar 49 is bolted to the upper end of the shaft 47, and is insulated therefrom by means of the insulating collar 51. The switch bar 49 extends transversely over the 65 head 44, and is adapted to coöperate with

the contact members 52 which are mounted upon an insulating plate 53, which is preferably formed of slate or similar material. The contact members 52 comprise pairs of 70 blades or studs between which the ends of the switch bar 49 is adapted to seat. One of the contact members 52 is connected to the feed wire 5 from the trolley pole, while the other contact is connected to a conductor 54 which carries the current to the controller. 75 When air from the branch pipe 42 passes into the cylinder 43 below the piston 48, it elevates the shaft 47, and therewith the switch bar 49, so that the circuit through the wires 5 and 54 is broken. The lower end 80 of the shaft 47 carries a hand grip 55, so that the piston 48 may be manually actuated upon occasion.

When it is desired to return the parts to their normal or set positions, the air pressure is used to accomplish the resetting. Thus, a pipe 56 is connected to the pipe 38 so as to receive air from the air tank 35 and is controlled by a globe valve 57. The pipe 56 is branched at the pet cock 58, one 90 branch 59 leading to the circuit breaker 9, and the other branch 60 leading to the chamber 30 of the controller. The branch 59 connects into the cylinder 43 above the piston 48, so that when the globe valve 57 is 95 opened and the pet cock 58 is properly positioned, air will be introduced into the cylinder 43 to return the piston to the lower end of the cylinder and connect the switch bar 49 with the contact members 52. The 100 branch pipe 60 is connected into the chamber 30 preferably through the top plate, so that air pressure may be introduced in front of the piston 34 to return the shaft 18 to its lowered position, thereby seating the valve 105 26 and returning the rollers 19 into the path of the elevated obstruction.

In order to relieve the cylinder 43 and the chambers 28, 29 and 30 of pressure, a pipe 61 is provided to bridge the pipe 42 110 and the four-way valve 37, so that when the latter is properly positioned, to connect a vent 62 in the valve casing with the pipe 61, the branch pipe 42, and the pipe 39, are open to the atmosphere. Bridging the pipe 115 42 and the cylinder 10 below the piston 34 is a pipe 63, which serves the double purpose of venting the chamber 30 for the return of the piston 34 and also for introducing the air to the chamber 30 when the valve 120 26 is elevated.

The air check 41 may be of any desired or approved type, but in the present case I have used a valve in which a casing 64 is provided with a transverse diaphragm 65 125 providing a valve seat 66 upon which is normally seated the valve 67. The casing 64 is closed at its upper end by a removable plug 68 and has extending through its bottom the stem 69. The lower end of the valve 130

stem 69 projects into an extension 70 of the casing 64 whose open end is closed by a removable plug 71. The free end of the stem 69 carries a threaded nut 72, said nut 72 acting to adjust the tension of a coil spring 73 carried between said nut and the bottom of the casing 64. Thus, when locked in the air line 40 the valve or air check 41 permits the passage of air to the brakes, but prevents the return or back pressure. In the operation of this form of the apparatus, the control device 6 is set into operation by coming into contact with the obstruction 7 which is located between the tracks. The roller 19 mounting the obstruction throws upwardly the shaft 18, and therewith the valve 26. When the four-way valve 37 is set as shown in the drawings, the chamber 29 stands under pressure, since it is in direct communication with the air tank 35. As soon as the valve 26 is lifted, the air is permitted to pass through the pipe 39 and check 41 to the air brake control valve (not shown), thereby operating the latter to set the brakes. Air also passing through the branch 42 and into the pipe 63 and thence to the chamber 30 lifts the piston 34 to complete the upward stroke of the shaft 18 and to hold the latter in lifted position. Air also continues through the branch 42 to the cylinder 43, lifting the piston 48. When the piston 48 is elevated the switch bar 49 is carried therewith through the medium of the extension 50, thereby interrupting the circuit from the trolley pole to the electric controller. After the brakes have been set, and the circuit interrupted, so that the car has been brought to a stop and it is desired to reset the various parts to their normal positions, that is, in the positions whereby the apparatus may be again actuated by the lifting of the shaft 18, the four-way valve 37 is turned so as to connect the pipe 61 with the vent 62, the globe valve 57 is opened and the pet cock 58 is set to clear the pipes 56 and 59. By thus setting the pet cock 58 air is permitted to pass into the cylinder 43 above the piston 48 to lower the latter. If necessary the hand grip 55 may be actuated to pull the piston 48 to its lowered position. After the circuit breaker has thus been set, the pet cock 58 is turned to clear the pipes 56 and 60, so that air may be introduced to the chamber 30 above the piston 34. Since the setting of the valve 37 to clear the pipe 61 to the atmosphere also opens the pipe 42 to the atmosphere, the pressure in the chambers 28 and 29 is relieved and the air behind the piston 34 is permitted to escape, so that the pressure from the pipes 56 and 60 may readily depress the piston 34. The piston 34 having been depressed, the four-way valve 37 is again turned into position to charge the pipe 36 and 38, thus again placing the chamber 29 under pres-

sure, so that the valve 26 is held upon its seat, and the roller 19 is held in the path of the elevated position of the obstruction 7.

In the form shown in Fig. 7 to 9 is disclosed the form of my invention which is particularly adapted for use upon steam locomotives. Preferably mounted upon the pilot 74, as upon a bracket 75 is a cylinder 76, having the same general characteristics as the cylinder 10 hereinbefore described. In this form, however, a downward extension 77 of the bracket 75 is formed at its lower end with a foot 78 in which is formed a bearing for a square rod 79 whose lower end carries a roller 80 of the same type as the roller 19. The rod 79 carries the shaft 81 having the valves 82 and piston 83. The cylinder 76 is subdivided into chambers 84, 85 and 86 in the same manner as the cylinder 10. A pipe 87 passing into the chamber 85 connects the latter with the full pressure from the air tank 88 under normal conditions. Below the valves 82, a pipe 89 connects into the chamber 86 and the branch so that a section 90 connects to the valve lifting device 91 hereinafter described, and another branch 92 passes to the main line air system. Adjacent the cylinder 76 the pipe 89 is provided with a by-pass 93, which has its opposite end connected to the chamber 84 below the piston 83, so that air pressure received into the pipe 89 when the valve 82 is lifted, will be communicated to the chamber 84 to lift and hold the piston 83.

Located in the cab of the locomotive are two three-way valves 94 and 95. The valve 94 is connected into the pipe 87 from the air tank, and is also connected into the pipe 92 which leads to the chamber 86, so that the pipe 92 may be connected to the atmosphere, one of the ports in the valve 94 communicating with the atmosphere. The three-way valve 95 also has one of its ports connected to the pipe 87, and furthermore is connected by a pipe 96 to the chamber 84 above the piston 83. A branch pipe 97 from the branch pipe 96 communicates with the device 91 as will hereinafter appear.

The valve closing device 91 comprises a cylinder 98 in which operates a piston 99, said piston 99 being carried upon a stem 100. The stem 100 passes through a diaphragm 101, and is swiveled at its lower end into a valve head 102. The valve head 102 operates in a casing 103 which is located in the steam pipe 104 which connects the locomotive boiler to the driving cylinders. The head 105 of the cylinder 98 forms a pressure chamber which communicates by means of the by-pass 106 with an auxiliary chamber 107, said chamber 107 being formed by a casing 108 which is threaded or otherwise secured inside of the cylinder 98. Said casing 108 carries a longitudinally slidable piston 109, which in turn carries a stem 110,

one end of which extends into the cylinder 98, and is adapted to latch the piston 99 in a normally uplifted position. A spring 111 surrounding the stem 110 and bearing between the piston 109 and the end of the casting 108 normally holds the piston and the latch end of the stem 110 in projected position. In order to provide access to the parts above described, the casing is provided with 10 a squared end by means of which it may be removed and replaced. The pipe section 90 hereinbefore described, is connected to the cylinder 98 and is connected into the chamber 107, in front of the piston 109, so that 15 when pressure is introduced into the chamber 107 the stem 110 will be retracted to release the piston 99. As the stem 110 is retracted, the piston 109 continues its rearward movement until the port or by-pass 20 106 leading into the cylinder 98 is uncovered so that the air pressure from the pipe 90 will operate upon the top of the piston 99 to seat the valve head 102, thereby cutting off the passage of steam from the boiler.

25 In the operation of this form of my invention, the control device operates substantially in the same manner as the device described in the form of Fig. 1. When the valve 82 is elevated, so that air pressure can pass from the chamber 85 to the chamber 86 and thence to the pipes 90 and 92, the brakes are set, and the air passes into the chamber 107 causing the piston 109 to retract, so that the stem 110 is retracted to 30 release the piston 99 so that when the air pressure from the pipe 90 can pass around the piston 109 into the passage 106 and thence to the cylinder 98 the piston 99 will be forced downwardly to close the valve head 102. When it is desired to reset the apparatus, the globe valve 112 located in the pipe 89 is closed, and the three-way valve 95 is turned from the position shown in Fig. 7 to clear the pipe 113 and pipe 96. 35 By this operation, air is permitted to pass from the air supply to the pipe 97 to elevate the piston 99 in the cylinder 98, thereby opening the steam valve, and also permits air to pass through the pipe 114 into the chamber 84 above the piston 83, thereby pushing the latter downwardly to reposition the roller 80 and reseat the valve 82. In order to relieve the pressure in the pipes 87 and 89, to permit the retraction of the parts 40 50 to their normal positions, the three-way valve 94 is turned to bring the vent port into communication with the pipe 92.

In Fig. 11 is disclosed the probable disposition of two of the valve closing mechanisms 91 on one of the old type locomotives, in which two steam pipes feed the steam to the cylinders.

Referring to Figs. 1 and 4, 115 indicates an elongated platform, preferably made of 65 heavy sheet metal, which is supported upon

the standards 116. The standards 116 are journaled in brackets 117 secured below the platform 115 and also in brackets 118 mounted upon a suitable base, as for instance, the cross ties of a railroad track. By means of the trunnioned standards 116, the platform 115 may be swung into elevated position, or lead down against the road bed. A crank 119 connecting to one of the standards provides a means for connecting the obstruction or platform to a setting mechanism which may be operated from a tower or other signal setting point. The opposite ends of the platform 115 carry hinged inclined plates 120 whose free ends are rounded to provide a free sliding surface, said ends riding upon horizontal plates 121 secured to the railroad ties or other base. The inclined plates 120 provide means for the gradual reception of the rollers 19 or 80 from either direction, and fold readily with the platform 115 when the latter is thrown into lowered position.

What I claim as my invention is:

1. A train controlling apparatus, comprising in combination, a power interrupting device, a cylinder associated with an air system and having a partition forming a pair of chambers, a rod operative in said cylinder and adapted to be actuated by an obstruction, a valve carried by said rod and subdividing said cylinder into chambers, means for maintaining one of said chambers under air pressure, means connecting the other chamber to said power interrupting device and to release the air to an air brake line, said valve permitting air to pass to said power interrupting device when lifted by said rod and a piston carried by said rod adapted to be connected to the air pressure for returning the valve to its seat.

2. A train controlling apparatus, comprising in combination, a power interrupting device, a cylinder associated with an air system, and having a partition forming a pair of chambers, a valve operative between the chambers of the cylinders, means for maintaining said cylinder under normal pressure on one side of said valve, an obstruction operated device for lifting said valve, to pass the pressure from one side of said valve to the other, means connecting the second chamber with said power interrupting device and to release air to an air brake line, and an isolated pressure chamber on said cylinder having a controlling piston for returning the valve to closed position.

3. A train controlling apparatus, comprising in combination, a cylinder connected in an air system and having a partition forming a pair of chambers, a rod extending through said cylinder, a valve carried by said rod and operative between the chambers of said cylinders, an isolated chamber also formed on said cylinder and having

said rod extending therein, a piston in said isolated chamber secured to said rod, means to maintain one side of said valve normally under air pressure, means to throw said valve off of its seat, and means for passing air to said isolated chamber to seat said valve.

4. A train controlling apparatus comprising in combination, a power interrupting device, and an air line for a brake system, means to release air to said air line, and means to reset said operating means, said operating means also setting into operation said power interrupting device simultaneously with the release of air to the air line, and comprising an air cylinder, having a

chamber under normal air pressure, a valve in said air cylinder closing said chamber, a second chamber communicating with said air brake system and said power interrupting device, and communicating with the first chamber when said valve is lifted, and a third chamber containing a piston adapted to be air actuated to return said valve to its seat.

20 In testimony whereof, I affix my signature, in the presence of two witnesses.
